UNITED STATES PATENT OFFICE.

CHARLES L. TEMPLETON, OF MINNEAPOLIS, MINNESOTA.

DISHWASHING MACHINE.

Application filed January 6, 1927. Serial No. 159,303.

My invention relates to improvements in dish washing machines and has for its object to increase the efficiency of the washing action thereof with a minimum amount of water, and it also provides novel means for rinsing the washed dishes with a minimum amount of clean, hot water.

In the accompanying drawings, which illustrate the invention, like characters indicate like parts throughout the several views.

Referring to the drawings:

Fig. 1 is a left-hand elevation of the improved dish washing machine, with some parts indicated by means of broken lines;

Fig. 2 is a transverse vertical section taken on the line 2—2 of Fig. 1;

Fig. 3 is a view in longitudinal vertical section taken on the line 3—3 of Fig. 2;

Fig. 4 is a right-hand elevation of the improved dish washing machine;

Fig. 5 is a detail view, partly in plan and partly in section, taken on the line 5—5 of Fig. 4;

Fig. 6 is a perspective view, with some parts sectioned, showing one of the connected pairs of arms and their basket-carrying tracks;

Fig. 7 is a view, partly in side elevation and partly in longitudinal central section, of the parts shown in Fig. 6;

Fig. 8 is a fragmentary detail view, in elevation, of the right-hand arm shown in Fig. 6;

Fig. 9 is a perspective view of one of the keepers;

Fig. 10 is a detail view principally in section, taken on the line 10—10 of Fig. 8; and

Fig. 11 is a fragmentary detail view of the switch and switch operating device shown in a different position from that indicated in Fig. 1.

The numeral 12 indicates a rectangular skeleton frame in which a sheet metal water tank 13 is mounted and held in an elevated position. The ends of the tank 13 are flat and parallel, and the body thereof in longitudinal vertical section is in the form of an ovoid with its apex at the bottom of said tank. To afford access to the interior of the tank 13, the segmental top section thereof, above the frame 12, is made displaceable. Extending transversely through the tank 13 at the axis of the segmental top section thereof is a horizontal shaft 14 journaled in

bearings 15 on the lower body section of said tank.

A receiving opening 16 is formed in the front of the tank 13 and a delivery opening 17 is formed in the back thereof. These opening 16 and 17 extend substantially the full width of the tank 13, are of the same height, and the delivery opening 17 is higher than the receiving opening 16, for a purpose that will presently appear. Receiving 65 and delivery tables 18 and 19, respectively, are hinged at 20 to the frame 12 at the lower edges of the openings 16 and 17, respectively, for outward and downward swinging movement and are held raised by releasable braces 70 21. It will be noted that the inner edge portions of the tables 18 and 19, when raised, extend slightly into the tank 13 through the openings 16 and 17, respectively, for a purpose that will hereinafter appear. In view 75 of the different elevations of the openings 16 and 17, the tables 18 and 19 are, of course, correspondingly located in respect to each other and the water line α in the tank 13 is just below the receiving opening 16. 80

An agitator in the form of a propeller 22 is mounted to rotate about a vertical axis at the bottom of the tank 13 at the transverse center thereof. Said propeller 22 has a depending shaft 23 journaled to a water-tight 85 bearing 24 on the under side of the tank 13 and said shaft is also journaled in the top and bottom members of a housing 25 secured to a shelf 26 on the frame 12. A worm gear 27 is secured to the intermediate portion of 90 the shaft 23 and meshes with a worm 28 on a horizontal shaft 29 journaled in bearings on the ends of the housing 25. Said shaft 29 extends parallel to the shaft 14 and is connected by a universal joint 30 to the armature shaft 31 of an electric motor 32 mounted on the shelf 26. 95

Formed with the tank 13, on the back thereof, is a narrow, but deep, overflow compartment 33 which extends substantially the full width of said tank. The top of the compartment 33 is just below the delivery table 19 and is closed thereby when said table is raised. A large waste pipe 34 leads from the bottom of the overflow compartment 33. In the back of the tank 13, just above the water level α , is a narrow opening 35 which extends substantially the full width of the tank 13. The purpose of this opening is for the overflow of the washing water from the 100 105 110

tank 13 to the compartment 33 and for the discharge of the rinsing water into said compartment, as will presently appear.

Two pairs of laterally spaced integrally formed diametrically extended arms 36 are secured to the shaft 14, close to the inner faces of the ends of the tanks 13. Said arms 36 of each integrally formed pair are edgewise spaced in vertical planes and located 10 on opposite sides of the shaft 14, so that when in horizontal position, said arms are substantially at the vertical center of the delivery openings 17 and 18, respectively. The arms 36 of each laterally spaced pair 15 are, of course, in the same plane. In each arm 36 is formed a rectangular slot 37 which extends substantially the full length thereof.

A cross-head 38 is slidably mounted in each slot 37, and is provided with an anti-20 friction roller 39 arranged to run on opposite longitudinal edges of the arm 36 at said slot. The cross-heads 38 have outer side plates which overlap the arms 36 at their slots 37, and hold said cross-heads for 25 straight line sliding movement on said arms and against lateral inward movement.

Trams 40 are provided for controlling the movements of the cross-heads 38 and cause the same to maintain constant relation to 30 the contour of the ovoid formation of the tank 13. Each tram 40 comprises a stem 41 having on its outer end a bifurcated head 42 in which is journaled a roller 43. The inner ends of the stems 41 extend into recesses in the outer ends of the cross-heads 38 and are connected to said cross-heads by 35 trunnions 44. The stems 41 extend longitudinally through the slots 37 and work between antifriction rollers 45 in the apertured outer ends of the arms 36. The rollers 43 of the trams 40 are arranged to run on flat track rails 46 secured to the tank 13 at the ends thereof, and follow the contour of the ovoid formation of said tank. The heads 42 40 of the trams are arranged to engage the outer ends of the arms 36 as stops to limit the inward sliding movement of the cross-heads 38. During the travel of the arms 36 when below their horizontal positions, the 45 trams 40 are projected under the action of gravity, and this movement is controlled by the rollers 43 on the track rails 46.

For each laterally spaced pair of arms 36 is a relatively heavy pivotally mounted gravity-suspended U-shaped track-carrying bar 55 47, the arms of which are rigidly secured to the trunnions 44, which support said bar for horizontal swinging movement. A pair of basket-carrying track rails 48 are rigidly secured in horizontal positions to the arms of 60 each U-shaped bar 47. The track rails 48 of each pair are in the form of angles, the vertical flanges of which are turned upward and the horizontal flanges of which are extended 65 toward each other.

At the ends of each track rail 48 is a pair of L-shaped keepers 49, the vertical members of which project above the horizontal flanges of the track rails 48, and the horizontal members of which underlap said horizontal flanges. Rigidly secured to each keeper 49 is a weighted arm 50 pivoted at the backs of the vertical flanges of the track rails 48. These weighted arms 50 are arranged to yieldingly hold the keepers 49 operative, as best shown in Figs. 6 and 8, and the horizontal members of said keepers engage the horizontal flanges of the track rails 48 as stops to limit the lifting movement of said keepers by the weighted arms 50. By pressing down on the keepers 49 against the action of the weighted arms 50, said keepers may be moved below the upper faces of the horizontal flanges of the track rails 48 so that 70 said track rails are unobstructed, for a purpose that will presently appear. At the time the keepers 49 are moved below the track rails 48, the weighted arms 50 are moved beyond dead centers and the horizontal members of said keepers engage said track rails as stops, and thereby hold said keepers inoperative, as shown by broken lines 75 in Fig. 8.

A wire dish-holding basket 51 is removably mounted on and suspended between each pair of track rails 48, and is designed to individually hold dishes y , as best shown in Fig. 2. When the baskets 51 are placed on the track rails 48, the vertical flanges of said rails hold said baskets against endwise shifting movement and the keepers 49 hold said baskets against lateral shifting movement. These dish-holding baskets 51 may be supported on either table 18 or 19 and freely moved through either opening 16 or 17 in the tank 13. The shaft 14 is driven to slowly rotate the arms 36 from the shaft 23, driven from the motor 32, by a sprocket chain 52 which runs over a large sprocket wheel 53 rigidly secured to the right-hand end of said shaft, outward of the tank 13, and a relatively small sprocket wheel 54 on the outer member of a two-part shaft 55, which extends parallel to the shaft 29 and is journaled in a bearing 56 on the frame 12. 100 The inner member of the shaft 55 is journaled in the housing 25 and is provided with a beveled gear 57 which meshes with a beveled gear 58 on the shaft 23. The members of the shaft 55 may be connected and disconnected, at will, by a clutch 59, the movable member of which is provided with a shipper collar. To this shipper collar is applied a laterally movable shipper lever 60 having a cross rod 61 slidably mounted in 105 bearings 62 on the front of the frame 12. 110

At the bottom of the tank 13 is a valve-equipped drain pipe 63 through which the washing water in the tank 13 may be drained 115 from said tank. 130

The arms 36 are rotated in the direction of the arrow marked on Fig. 3 from a position in which the basket 51 at the opening 16 is carried thereby downward through the body 5 of the water in the tank 13 and then upward and out of the water on the opposite side of said tank and positioned in front of the opening 17. At this same time the other basket 51, at the opening 17, is moved above 10 the water and positioned in front of the opening 16. During this movement of the baskets 51, the same are held from turning by the turning of the trunnions 44 in the cross-heads 38, under the action of the heavy 15 U-shaped bars 47 and the suspension of said baskets below said trunnions.

After a basket 51 has been lifted from the washing water during its travelling movement, the dishes γ are rinsed by clean, hot 20 water in a novel manner which includes upper and lower nozzle pipes 64 and 65, respectively, arranged to spray toward each other, as indicated by the arrows, as best shown in Fig. 3. These nozzle pipes 64 and 65 extend 25 parallel to the shaft 14, and project outward through segmental open slots 66 and 67, respectively, in the right-hand end of the tank 13. Said nozzle pipes 64 and 65 are in the form of laterals on an upright oscillatory water pipe 68, the lower end of which is extended laterally and journaled in a water-tight bearing 69 on the discharge end 30 of a hot water supply pipe 70 leading from any suitable source of supply under pressure. 35

Interposed in the water supply pipe 70 is a rotary valve 71 having a crank arm 72 connected by a link 73 to the long end 40 of a lever 74 intermediately pivoted to a part on the frame 12. The short end of the lever is provided with a cam groove 75 in which is a cam pin 76 on a clamp 77 applied to the oscillatory water pipe 68. The action 45 of the cam pin 76 on the cam groove 75 in the lever 74, during the oscillation of the water pipe 68, is such as to operate said lever and intermittently open and close the valve 71 in timed relation to the oscillations of said pipe. Normally, the pipe 68 is positioned, as indicated in Fig. 3, with the 50 nozzle pipes 64 and 65 outside of the tank 13, and at which time the valve 71 is closed. During the movement of these nozzle pipes 64 and 65 to the inner ends of the slots 66 and 67 and their return, the valve 71 is open 55 so that rinsing water is discharged from said nozzle pipes.

The oscillatory water pipe 68 is yieldingly held in its inoperative position, as shown by 60 full lines in Fig. 3, by a weight 78 adjustably mounted on a radially extended arm 79 rigidly secured to the clamp 77. A strap 80 is secured to the tank 13, across the open outer end of the slot 66 to be engaged by

the nozzle pipe 64 as a stop to limit the 65 outward swinging movement of the oscillatory pipe 68, under the action of the weight 78.

To move the water pipe 68 from its inoperative position as shown by full lines in Fig. 70 3 to its innermost position, as shown by full lines in Fig. 4, and then release the same, there is provided an upright lever 81 intermediately pivoted at 82 to the right-hand end of the tank 13. The lower end of this 75 lever 81 is connected by a link 83 to the clamp 77 and its upper end has a cam finger 84 arranged to be alternately engaged by a pair of cam lugs 85 on certain of the arms 80 of the sprocket wheel 53, and which lugs are located 180 degrees apart.

The timed relation between the movement of the basket 51 in the tank 13 and the oscillations of the water pipe 68 is such that the basket 51, just moved out of the washing 85 water, is between the nozzle pipes 64 and 65 during their spraying action to rinse the dishes γ in said basket.

To collect the rinsing water from the nozzle pipes 64 and 65, and discharge the same 90 there is provided a concavo-convex drain board 86 hinged at 87 to the tank 13 and extends into said tank through the overflow opening 35. This drain board 86 is arranged for vertical swinging movement from a position, in which it hangs down in washing water in the tank 13 and rests in an inoperative position against the inner wall of said tank, to an operative position, as shown 95 by full lines in Fig. 3, in which it is in an 100 inclined position above the water line x . On the ends of the drain board 86 are shallow flanges 88 which hold the rinsing water thereon.

To raise the drain board 86 to an operative 105 position in timed relation to the movement of one of the baskets 51 out of the washing water to a rinsing position, there is secured to one end of the hinge rod of said drain board a crank-acting cam arm 89. This 110 cam arm 89 is arranged to be engaged by one end of a lever 90 intermediately secured to the left-hand end of the shaft 14. Once during each half rotation of said shaft, the drain board 86 is lifted to an operative position 115 and thus held during each rinsing action and then said arm is released to permit the drain board 86 to return by gravity to an inoperative position in the washing water.

This drain board 86 also performs another 120 important function in that it acts as a skimmer to lift solids from the washing water and discharges the same through the opening 35 into the overflow compartment 33. During the lifting movement of the drain board 86, 125 there will be sufficient washing water thereon to carry with it the solids and discharge the same through the overflow opening 35.

Furthermore, the rinsing water will also carry off any solids remaining on the drain board 86.

To start and stop the motor 32 when the baskets 51 are in loading and unloading positions, there is provided an automatic switch-operating device that is automatically operated to open the switch and manually released to automatically close the switch. 5 This device includes a double switch 91 mounted on the frame 12 and electrically connected by wires 92 to the motor 32. Said switch 91 is alternately opened and closed by an oscillatory fork 93 pivoted to said frame with its prongs embracing the switch to engage the diametrically opposite push buttons thereof, as best shown in Fig. 11. A coil spring 94, attached to the fork 93 and anchored to the frame 12, is under strain 10 to move said fork into a position to open the switch 91, as shown in Fig. 1. To oscillate the fork 93 against the tension of the spring 94 and thereby close the switch 91, there is mounted in a pair of aligned ears 95 on 15 the fork 93, a flat stop plate having on its outer end a finger piece 96. This stop plate 96 is held by a coil spring 97 projected in the path of movement of the lever 90 to be engaged thereby once during each half rotation of said lever, or in other words, to be alternately engaged by the ends of said lever. At the time the stop plate 96 is engaged by the lever 90, the fork 93 is oscillated against the tension of its spring 94 and thereby 20 operates the switch to stop the motor, as shown in Fig. 11, with the baskets 51 opposite the openings 16 and 17 in the tank 13. To close the switch 91 and thereby start the motor 32, the stop plate 96 is manually 25 operated against the tension of its spring 97 to release the fork 93, held by the lever 90, and permit its spring 94 to oscillate said fork and thereby close the switch 91.

Operation.

The operation of the above described dish washing and rinsing machine may be briefly described as follows: It may be assumed that the machine is idle with the clutch 59 released, the arms 36 positioned with the basket-carrying tracks 48 in horizontal positions in which one pair thereof is opposite the opening 16 and the other pair thereof is opposite the opening 17, as shown in Fig. 3, with the nozzle pipes 64 and 65 held in inoperative positions outside of the tank 13 by the weight 78, as shown by broken lines in Fig. 3, with the valve 71 closed and the switch 91 held closed by the fork 93 which in turn is held by the lever 90 against the action of the spring 94. It may also be assumed that the drain pipe 63 is closed and the tank 13 filled with hot water up to the water line x and containing the necessary amount of washing powder. 30

With the machine thus set, the operator first retracts the stop plate 96 to release the fork 93 from the lever 90 and permit the same, under the action of the spring 94, to close the switch 91 and start the motor 32, and drive the propeller 22 to agitate the water in the tank 13 and mix the washing powder therewith to produce suds. The basket 51 at the opening 16 is then removed and filled with dishes to be washed. The 35 filled basket 51 is then placed on the receiving table 18 in its proper relation to the adjacent track rails 48, and the outer keepers 49 are moved into inoperative positions and held by their arms 50. Said basket 51 is then slid from the table 18 into the tank 13 through the opening 16 and over the track rails 48 and the keepers 49 are closed. It is important that the extension of the table 40 into the tank 13 keeps the filled basket 51 out of contact with the rails 48 before said basket is lowered thereon in order not to tip said rails, which are gravity held. In filling the basket 51, the operator so places the dishes that the load will be quite evenly distributed in the basket on both sides of the trunnions 44. The clutch 59 is then set by moving the rod 61 endwise to operate the shipper lever 63 to drive the shaft 14 and thereby rotate the arms 36 by means 45 of the driving connections 52, 53 and 54 from the outer section of the shaft 55, which has just been connected to the inner section of said shaft by the clutch 59.

During the rotation of the arms 36, the 50 filled basket 51 is carried downward into the water and then out of the same on the opposite side of the tank 13. During this movement of the filled basket 51 through the water, the respective trams 40, acting on 55 their cross-heads 38, permit the basket to travel away from the axis of the shaft 14 and thereby enter the water to substantially its full depth. Due to the peculiar shape of the tank 13, a minimum amount of water 60 is required to fill the same and hence a relatively small quantity of the washing powder is required. This mounting of the basket 51 for movement toward and from the axis of the shaft 15 permits said basket to travel 65 a greater distance through the water and hence has the same effect as a large body of water.

The propeller 22, due to its location at the bottom of the tank 13 and the operation of its blades close to the relatively-steep front and back walls of said tank, not only sets up a whirling motion of the water in said tank, but forces the water in opposite directions up the front and rear walls of the 70 tank 13, and thereby causes the same to break and fall back into the center of the tank 13 over the propeller 22. It will thus be seen that during the movement of the filled basket 51 through the washing water, said 75

water is forced through the basket and around the dishes in all directions which thoroughly and quickly cleanses the same.

When the filled basket 51 is opposite the drain board 68 during its movement out of the water, the cam arm 89 is engaged by one end of the lever 90 and operated to cause said drain board to follow the filled basket 51 out of the water and be held in an operative position under said basket. During this same time, the cam finger 84 on the lever 81 is engaged by one of the cam lugs 85 and the said lever operated to swing the water pipe 68 inward and thereby carry the nozzle pipes 64 and 65 into the tank 13 at the time the filled basket is between the same. As the water pipe 68 swings inward, the valve 71 is opened by the connections 72, 73 and 74 under the action of the cam pin 76. With the opening of the valve 71, a spraying action is set up by the nozzle pipes 64 and 65 in which jets of hot water, under pressure, are directed onto the dishes in the filled baskets 51 from the top and the bottom of said baskets and at various different angles during the travel of said nozzle pipes. It will thus be seen that the dishes in the filled baskets 51 are thoroughly and quickly rinsed with hot water.

At the time the cam lug 85 moves out of engagement with the cam finger 84 and releases the lever 81, the weight 78 returns the water pipe 68 to a normal position in which the nozzle pipes 64 and 65 are again positioned outside of the tank 13. When the arms 36 have made one-half rotation, the lever 90 engages the stop plate 96 and thereby rocks the fork 93 which operates the switch 91 and closes the same to stop the motor 32. At the completion of this one-half rotation of the arms 36, the filled basket 51, which has just been rinsed, is positioned directly opposite the opening 17 and the empty basket 51 is directly opposite the opening 16. The outer keepers 49, holding the filled basket 51, are now turned into inoperative positions and the basket filled with rinsed dishes is drawn from the track rails 48 onto the delivery table 19, which projects into the tank 13, and through the opening 17. At the time the filled basket 51 is removed from the opening 17, the empty basket 51 is so positioned that the same may be removed through the opening 16 and filled with dishes to be washed.

The above described machine is so designed that the same may be placed in various different positions in respect to wall space as either side thereof may be turned against a wall without interfering with the operation of the machine, and in case there is not sufficient room for the use of the delivery opening 17 the basket of rinsed dishes may be carried on around in the machine

and removed through the opening 16. The construction and action of the machine is such that an electric motor of small horse power may be used to operate the same. The novel and efficient manner in which the dishes are rinsed requires the use of very little water.

It will be noted that the clutch 59 is so arranged that the baskets may be operated or stopped while the agitator is in operation without effecting the action thereof. This arrangement of the clutch 59 is highly important in that in case the dishes require a longer time in which to cleanse the same than that during a continuous travel through the water, said clutch may be operated to stop the driving connections to the shaft 14 while one of the baskets is in the washing water and thereby allow the dishes to soak.

What I claim is:

1. A dish washing machine having a water tank that, in vertical cross-section, is substantially in the form of an ovoid with its apex at the bottom of the tank, and a basket mounted in the tank to swing about a given axis, move radially in respect to said axis and follow the ovoid contour of the tank.

2. The structure defined in claim 1 in further combination with an agitator in the tank at the bottom thereof.

3. A dish washing machine having a water tank, a revolute member in the tank, said tank having varying diameters from the axis of the revolute member, a gravity-suspended basket mounted on said member for travelling movement toward and from the axis thereof, and means operative to cause the basket to maintain a definite relation to the contour of the tank during the rotation of said member.

4. A dish washing machine having a water tank, a pair of revolute arms in the tank, said tank having varying diameters from the axis of the arms, cross-heads mounted to travel longitudinally on the arms, a basket pivotally mounted on the cross-heads, and trams operative to cause the cross-heads to maintain a definite relation to the contour of the tank during the rotation of said arms.

5. The structure defined in claim 4 in further combination with tracks in the tank for the trams and following the contour of said tank.

6. A dish washing machine having a water tank, two pairs of laterally spaced diametrically extended revolute arms in the tank, said tank having varying diameters from the axis of said arms, cross-heads mounted to travel longitudinally on the arms, basket-holding tracks pivotally mounted on the cross-heads, removable baskets on said tracks, and trams operative to cause the cross-heads to maintain a definite relation to the contour of the tank during the rotation of said arms.

7. A dish washing machine having a water

tank, a pair of revoluble arms in the tank, gravity-suspended basket-holding tracks carried by the arms, a removable basket on said tracks, and displaceable keepers at the ends 5 of the tracks for holding the baskets from shifting thereon.

8. The structure defined in claim 7 in further combination with yielding means for holding the keepers in operative and in- 10 operative positions.

9. A dish washing machine having a water tank, a pair of revoluble arms in the tank, a gravity-suspended U-shaped bar, the ends of which are journaled on the arms, basket- 15 holding tracks on the U-shaped bar, and a removable basket on the tracks.

10. A dish washing machine having a water tank provided with diametrically opposite basket intake and discharge openings, a 20 shaft in the tank, two laterally spaced pairs of diametrically extended revoluble arms on the shaft, and a basket removably mounted on each laterally spaced pair of arms, the arms of each diametrically extended pair of 25 arms being edgewise spaced on opposite sides of the shaft.

11. A dish washing machine having a water tank, a travelling basket-carrier, driving connections for said carrier, a drain board 30 in the tank, and automatic means for operating the drain board in timed relation to the travel of the carrier.

12. A dish washing machine having a water tank, a basket mounted to move through 35 the water in the tank and out of the same, a rinsing water pipe having a sprayer arranged for action on the basket after coming out of the water, a valve normally closing said sprayer, means for opening and closing 40 the valve in timed relation to the movement of the basket, a drain board, and means for

positioning the drain board under the basket after leaving the water and then returning the basket to normal position in timed relation to the opening and closing of the valve. 45

13. A dish washing machine having a water tank, a basket mounted for movement through the water in the tank and out of the same, a rinsing water supply pipe having an oscillatory section provided with a sprayer arranged to move transversely of the path of movement of the basket after coming out of the water, yielding means normally holding said oscillatory section with the sprayer out of said path, automatic means for swinging said section to carry the sprayer through said path and then release the same for return movement, a valve normally closing the sprayer, and connections operated by said oscillatory pipe section for opening and closing the valve. 50

14. A dish washing machine having a water tank, a basket mounted for movement through the water in the tank and out of the same, a rinsing water supply pipe having an oscillatory section provided with upper and lower nozzle pipes arranged to move transversely of the path of movement of the basket after coming out of the water, yielding means normally holding said pipe section with the nozzle pipes out of said path, automatic means for swinging said section to carry said nozzle pipes into the tank at the time the basket is between the same and then release said section to permit the return thereof, a valve normally closing said section to the nozzle pipes, and connections operated by said section for opening and closing said valve in timed relation therewith. 55 70 75 80

In testimony whereof I affix my signature.
CHARLES L. TEMPLETON.
